UNITED STATES PATENT OFFICE.

AUSTIN H. MYERS AND PAUL A. COLLINS, OF HANOVER, PENNSYLVANIA.

WASHING APPARATUS.

1,410,711.

Specification of Letters Patent. Patented Mar. 28, 1922.

Application filed April 11, 1921. Serial No. 460,173.

To all whom it may concern:

Be it known that we, AUSTIN H. MYERS and PAUL A. COLLINS, citizens of the United States, residing at Hanover, in the county 5 of York and State of Pennsylvania, have invented certain new and useful Improvements in Washing Apparatus, of which the following is a specification.

This invention relates to washing apparatus, and it comprises a tube or pipe adapted to be connected to a supply of water, a nozzle mounted on the end of said tube, a sleeve slidably mounted on said tube, a pair of spring arms secured to said sleeve, said arms 10 being adapted to receive and support a sponge, and a locking member engaging said arms to retain the sponge in position.

In the present invention, we have provided a device particularly suitable for washing 20 automobiles, motor trucks, and similar vehicles, although it may also be employed in a number of different ways. The apparatus comprises a pipe having a suitable nozzle for directing a spray of water onto a vehicle or 25 other article to be cleaned, and a sponge for washing is mounted on the pipe to which the nozzle is attached. The sponge is supported by a pair of spring arms having suitable locking means to retain the sponge in engagement therewith, and these arms are 30 secured to a sleeve which is slidably mounted on the nozzle whereby the sponge can be moved outwardly when desired.

In the accompanying drawings, we have 35 shown several embodiments of the invention. In this showing:

Figure 1 is a side elevation, parts being shown in section,

Figure 2 is a vertical sectional view on 40 line 2—2 of Figure 1,

Figure 3 is a detail sectional view on line 3—3 of Figure 1, and,

Figure 4 is a detail view showing a modified type of nozzle.

Referring to the drawings, the reference 45 numeral 1 designates a pipe or tube through which the water passes to the nozzle. This pipe may be connected to any suitable supply of water, as indicated at 2. A substantially 50 funnel shaped nozzle 3 is arranged on the outer end of the pipe, the nozzle being formed of hard rubber or other suitable material, and being provided with an annular flange or bead 4 at its outer end. A per- 55 forated disk 5 is retained in the mouth of the nozzle by the flange or bead to form a

spray. The inner end of the nozzle is of substantially the same diameter as the external diameter of the pipe 1, and is adapted to be slid over the end of the pipe. A bead or 60 flange 6 is arranged on the end of the nozzle, and this flange is adapted to be engaged by curved spring arms 7, secured to the pipe by any suitable means, as at 8.

A sleeve 9 is slidably mounted on the pipe, 65 being retained in adjusted position by means of a set screw 10. A pair of spring arms 11 are secured in the sleeve in any suitable manner, as by threads 12, and the outer ends of these arms are adapted to receive and support a sponge, indicated at 13. The normal tendency of the arms is to spread or diverge from each other, and a locking plate 14 is provided to retain the arms adjacent each other, and thus support the sponge. As 70 shown, the plate is provided with a slot 14', through which one of the arms passes, and a slot 15, having an offset portion 16 extending outwardly to the edge of the plate. It will be apparent that the sponge can be placed 75 in position or removed by disengaging the arm 11 from the slot 15, and allowing the arms to separate. The arms are provided with curved ends 17 to assist in retaining the sponge in position.

In the form of the invention shown in Figure 4 of the drawings, the nozzle is secured to an internally threaded sleeve or ferrule 18. The end of the pipe is externally threaded and these threads are adapted to 80 engage the internal threads of the nozzle, as at 19.

The operation of the device will be apparent from the foregoing description. In washing vehicles, a spray of water is first directed on the vehicle through the nozzle 3, and the vehicle is then rubbed or washed with the sponge 13. The sponge may be adjusted outwardly when in use, if desired, and withdrawn when not in use.

It is to be understood that the forms of our invention herewith shown and described are to be taken as preferred examples of the same, and that various changes in the shape, size, and arrangement of parts may be resorted to without departing from the spirit of the invention or the scope of the subjoined claims.

Having thus described our invention, we claim:

1. In a device of the character described, a pipe adapted to be connected to a supply

of water, a nozzle arranged on the end of said pipe, a sleeve slidably mounted on said pipe, a pair of spring arms secured to said sleeve, and a locking plate, said plate being provided with an opening for the passage of one of said arms and being further provided with an elongated slot for the reception of the other of said arms, whereby said arms may be retained adjacent each other to receive and retain a sponge.

2. In a device of the character described, a pipe adapted to be connected to a supply of water, a nozzle arranged on the end of said pipe, a sleeve mounted on said pipe, said sleeve being provided with a pair of

threaded openings, a pair of diverging spring arms having threaded ends adapted to be received in said openings, and a locking plate to retain said arms adjacent each other, said plate being provided with an opening 20 for the reception of one of said arms and an elongated slot for the reception of the other arm.

In testimony whereof we affix our signatures in presence of two witnesses.

AUSTIN H. MYERS.
PAUL A. COLLINS.
